G. E. STEENROD

WINDMILL

Filed Sept. 9, 1926

Inventor

George E. Steenrod
By Arthur L. Sprinkle
Atty.

UNITED STATES PATENT OFFICE.

GEORGE E. STEENROD, OF FREEPORT, ILLINOIS, ASSIGNOR TO WOODMANSE MANUFACTURING COMPANY, A CORPORATION OF ILLINOIS.

WINDMILL.

Application filed September 9, 1926. Serial No. 134,424.

This invention relates to improvements in windmills and particularly to the pump rod driving mechanism thereof, and to the arrangement of the means for controlling the 5 operation of the mill.

One of the objects of the invention is to provide a construction and arrangement wherein the thrusts of the driving mechanism are uniformly distributed, thereby contributing 10 to the efficient operation and durability 15 of the device.

Another object of the invention is to provide an arrangement of the control means and pump rod whereby interference of these elements, one with the other, is avoided.

A further object of the invention is to provide an arrangement wherein the actuating means of the pump rod is substantially in line with the pump rod support, thereby contributing 20 to the freedom and ease of operation.

A further object of the invention is to improve devices of this character in sundry details hereinafter described and particularly 25 pointed out in the appended claims.

One embodiment of the invention is shown for illustrative purposes in the accompanying drawing, in which

Fig. 1 is a plan view of a windmill head illustrating an embodiment of my invention.

Fig. 2 is a vertical sectional view taken substantially on the line 2—2 of Fig. 1, showing the pump rod in elevated position.

Fig. 3 is an enlarged perspective view of the 35 pump rod drive mechanism detached from the head.

In the illustrative embodiment shown, a frame member or casing 5 is provided with a horizontally extending housing 6 forming a 40 support for the bearings of a rotatable wind wheel or power shaft 7, to one end of which is secured a wind wheel 8 and to its opposite end a pinion 9 adapted to mesh with the internal teeth 10 of a rotatable member 11.

The casing 5 is preferably in the form 45 of a receptacle having longitudinally extending side walls 12 and 13 and end walls 14 and 15. The side walls 12 and 13 are provided respectively with aligned bearings 16 and 17 adapted to receive and have secured therein by tapered pins 18 the opposite ends of a short shaft 18 on which is rotatably mounted, between the bearings, the rotatable member 11. Formed, preferably on the wall 15, are 50 a pair of upstanding bearing lugs 19 having

aligned openings adapted to receive a shaft 20 on the outer ends of which is mounted one end of an oscillating or rocker arm 21, while to the opposite or free end of the arm 21 is pivotally connected the upper end of the 60 vertical pump rod 22. For converting the rotary motion of the power shaft 7 into reciprocating motion for actuating the pump rod 22, the rotatable member 11 is provided with an eccentric disc 23 adapted to receive 65 an eccentric strap 24 having an arm or pitman 25 formed thereon, the said arm or pitman extending outwardly from the disc and having its outer end adapted to engage an aperture 70 in the oscillating arm 21 and to be pivotally connected to said arm by means of a short shaft 26.

It will be observed from the foregoing description that the shaft 18 is suitably supported at its opposite ends, thereby providing 75 a most efficient and practical mounting for the rotatable member 11, and that the thrust of the eccentric disc and its connections with the reciprocating pump rod 22 is in substantial alignment with the plane of 80 movement of the oscillating arm 21, thereby reducing to a minimum any cramping action 85 of the pump rod driving mechanism.

The casing 5 is provided, preferably adjacent the side wall 13, with a vertically extending sleeve portion 27 having an enlarged central bore 28 adapted to receive the upper end of the tubular mast 29. By reference to Fig. 1 it will be noted that the pump rod 22 extends downwardly through the bore 90 and mast at one side of the center thereof and that a sheave 30 is mounted in the upper end of the bore 28. A chain 31 for controlling the operation of the mill extends upwardly through the mast and is trained over 95 the sheave 30 and around a second sheave 32 and at its end portion is connected to the wind vane 33 in a manner to manipulate the vane for permitting the wind wheel to rotate and actuate the pump rod or to secure 100 the wheel against rotation. This wheel controlling mechanism may be of any suitable design, such as shown, for example, in Fig. 1, in which an upstanding lug 34 on the vane 33 is adapted to engage one end of a rocker 105 arm 35, the opposite end of which is connected by means of a cross rod 36 with a bell crank lever 37 adapted to actuate suitable friction brake mechanism (not shown) within 110 the hub of the wind wheel 8.

It will be observed that in the arrangement of the control chain and pump rod that the vertical run of the chain occupies a position to one side of the rod and transversely to the plane of movement of the oscillating arm 21 for actuating the rod, thereby avoiding any interference of the rod and chain by reason of any lateral movement of the rod due to its connection with the oscillating arm 21.

10 For suitably oiling the connections of the pump rod driving mechanism, the casing 5 provides a receptacle or sump for containing a supply of oil 38 adapted to be carried upwardly by fins 39 formed on the rotatable member 11, and, as the fins reach their uppermost position, to deposit the oil by gravity on the upper side of the eccentric and the arm 21. To facilitate the distribution of the oil to the various connections, the arm 21 is 15 provided adjacent its edges with upstanding flanges 40 adapted to retain the oil on the upper side of the arm to insure its transmission to oil openings formed in the bearing portions of the arm at its connections with the shaft 20 and its pivotal connection with the pump rod 22. For conveying the oil deposited by the fins 39 to the top of the arm, the arm 21 is provided with a plurality of laterally disposed channels 41 extending beneath the fins, as clearly shown in Fig. 1, while a channel 42 positioned preferably between the channels 41 provides for the transmission of oil to the pivotal connection of the arm or pitman 25 with the oscillating arm.

35 It will be observed from the foregoing description that the present invention provides a construction and arrangement wherein the connections of the pump rod driving mechanism are in substantial alignment and wherein the thrusts of said mechanism are uniformly distributed, thereby contributing to the efficient operation and durability of the device, and wherein any interference between the pump rod and the control means is 40 avoided.

45 It will be observed further that the present invention provides efficient oiling means for all of the connections of the driving mechanism, thereby reducing to the minimum the wear of the various elements at these points.

Obviously, the present invention is not limited to the precise construction and arrangement shown and described but may be variously modified without departing from the spirit and scope of the invention as set forth in the claims. Moreover, all the features of the invention need not be used 50 jointly, as the same may be used to advantage in variously different combinations and sub-60 combinations.

What I claim as my invention and desire to secure by Letters Patent is:

65 1. In a windmill, the combination with a casing, of a rotary power shaft, a pump rod, and means driven by said shaft for reciprocating

ing said rod, said means comprising an arm pivotally related to the casing and having a pivotal connection at one of its ends with said rod, and an eccentric operatively connected by gearing with said shaft and having an operative connection with said arm in a manner to oscillate the arm on its pivot.

2. In a windmill, the combination of a frame, a power shaft having a pinion secured to one end thereof mounted in said frame, a second shaft mounted at its opposite ends in supports formed in said frame, a rotatable member mounted on said second shaft intermediate its supports and having teeth adapted to co-operate with said pinion, an eccentric disc formed on said member, an arm pivotally mounted on said frame, a pump rod pivotally connected to the free end of said arm, an eccentric strap mounted on said disc and operatively connected with said arm in a manner to rock the arm on its pivot to reciprocate said rod.

3. In a windmill, the combination of a frame, a power shaft having a pinion secured to one end thereof mounted in said frame, a second shaft mounted at its opposite ends in supports formed in said frame, an eccentric disc rotatably mounted on said second shaft intermediate said supports and operatively connected with said pinion in a manner to be driven thereby, an arm pivotally mounted on said frame, a pump rod pivotally connected to said arm, and an eccentric strap operatively connected to said disc and arm in a manner to reciprocate said rod when said power shaft is rotated.

4. In a windmill, the combination of a frame, a windwheel shaft having a pinion secured to one end thereof mounted in said frame, a second shaft supported at its opposite ends in said frame, a gear having an eccentric disc formed thereon mounted on said second shaft intermediate its ends and adapted to co-operate with said pinion in a manner to be driven thereby, an arm pivotally mounted on said frame, a pump rod pivotally connected to one end of said arm, an eccentric strap mounted on said disc and pivotally connected to said arm in a manner to oscillate the arm and reciprocate the rod when said windwheel shaft is rotated.

5. In a windmill, the combination of a frame, a vane pivotally mounted thereon, a sleeve formed in said frame, a hollow mast secured in said sleeve, an arm pivotally mounted on said frame, means for oscillating said arm, a rod extending through said sleeve and mast and having its upper end pivotally connected to said arm, a plurality of sheaves mounted in said frame, and flexible controlling means extending through said mast and sleeve and trained over said sheaves in a manner to be operatively connected to said vane for swinging the vane on its pivot, one of said sheaves being positioned in said sleeve in

a manner to position said last named means adjacent said rod and laterally of the plane of movement of the upper portion of said pump rod due to its connection with said 5 oscillating arm.

6. In a windmill, in combination a casing, a power shaft rotatably supported in said casing, a pump rod, an arm pivotally related to the casing and having a pivotal connection at its free end with said rod, reducing 10 gearing for operating said arm and said pump rod carried thereby, comprising a spur pinion connected with the rotary power shaft on the interior of the casing, a disc comprising

ing a hub portion, an internally toothed peripheral portion at one side of said disc engaging the said spur pinion on the power shaft, there being an eccentric formed integrally with the said disc on the reverse side thereof from the internally toothed gear portion, and a strap engaging the said eccentric portion on the said disc and being operatively connected with the said arm. 15 20

In testimony whereof I have signed my name to this specification on this 25th day of 25 August, A. D. 1926.

GEORGE E. STEENROD.
